UNITED STATES PATENT OFFICE
2,613,096
STRIKE
Adolf Schoepe, Anaheim, Calif., assignor to Kwik-set Locks, Inc., Anaheim, Calif., a corporation of California
Application June 10, 1949, Serial No. 98,209
2 Claims. (Cl. 292—340)

1 This invention relates to an improved strike for use on door jambs in cooperation with door locks and to a die for producing the same.

Many situations arise wherein the space between a door jamb and its door is such that the bolt or latch of the door lock as mounted on the door is incapable of reaching the strike so as to be engageable therewith to retain the door in closed position. These situations arise from a number of different circumstances such as, for example, the settling of the building in which the door jamb is located, the shrinkage of the door and, in some instances, the initial fitting of the door and door jamb has been improperly performed. In many instances of wartime housing where green or insufficiently dried lumber was employed the shrinkage of the door and of the door jamb and the warping of these elements on drying has caused the space between the edge of the door and the side of the door jamb to open to such extent that the latch or bolt of the door lock, even in its fully extended position, will not quite engage the strike.

An object of the present invention is to provide an improved strike which differs from the conventional strike in that a bulge or protuberance is formed adjacent the locking edge of the strike so that this edge will be caused to extend toward the edge of the door and thus be engageable by the end of the bolt or latch of the door lock. As the strike is made of malleable metal this protuberance or bulge may be utilized or not, depending upon the circumstances of the particular door and door jamb in question and, if the edge of the door is sufficiently close to the door jamb so that the bulge or protuberance need not be used, the strike may be readily flattened adjacent its locking edge to conform to the conventional strike.

Another object of the invention is to provide a very simple die which may be utilized advantageously to form strikes embodying the present invention or which may be utilized to deform or modify a conventional strike so as to extend its locking edge toward the edge of the door and thus enable the bolt or latch of the door lock to engage it when the spacing between the door edge and the jamb is found to be too great.

With the foregoing and other objects in view, which will be made manifest in the following detailed description and specifically pointed out in the appended claims, reference is had to the accompanying drawings for an illustrative embodiment of the invention, wherein:

Figure 1 is an exploded view of the die em-

2 bodying the present invention and illustrating a conventional strike as about to be positioned therein to be deformed in accordance with the present invention;

5 Fig. 2 is a vertical section through the die and strike illustrating the strike as being deformed by the die;

Fig. 3 is a perspective view of a strike embodying the present invention; and

10 Fig. 4 is a perspective view illustrating the strike as shown in Fig. 3 as being returned to the shape of a conventional strike when the deformed locking edge thereof is not required.

Referring to the accompanying drawings 15 wherein similar reference characters designate similar parts throughout, 10 indicates a conventional strike for door locks consisting of a section of heavy sheet metal, usually generally rectangular in form, and having apertures 11 for the

20 reception of screws by which the strike is attached to the jamb. Near the center of the section there is a rectangular aperture 12 of such size and shape as to receive the latch or bolt of the door lock with which the strike is associated.

25 Along one edge of the section there is a laterally bent lip 13 which presents outwardly a convex surface merging smoothly into the surface of the strike and which is engageable by the bolt or latch of the door lock to cause it to be forced into retracted position as the door closes and from 30 which position the latch or bolt can be projected into the aperture 12 to engage its locking edge 14 and thus retain the door in closed position.

As above explained, however, many situations 35 arise wherein when the strike is mounted on the door jamb the bolt or latch of the door lock, even in its fully extended position, is still incapable of engaging the locking edge 14. To remedy this situation I provide a die consisting of a female

40 member 15 the top surface of which is flat complementary to the face of the body of the strike 10. Along one side the top surface of the female member is curved upwardly as indicated at 16

45 complementary to the underside of the upwardly curved lip 13 so that when the strike 10 is positioned thereon it will rest evenly on the female member. An aperture 17 is formed in the female member at such a position to register with the aperture 12 in the strike. On the other side of 50 the female member there is formed a concavity 18 that is generally triangular in plan and which extends from the side of the aperture 17 toward the upwardly curved surface 16. The male member of the die, indicated at 19, has at its lower

55 end a guide 20 of such size and shape as to be

receivable through the aperture 12 and in aperture 17 of the female die. This male member presents a convex under surface 21 complementary to the concave surface 18, and extending laterally from the side of the guide 20.

When it is desired to deform a conventional strike to produce a strike in accordance with the present invention, the conventional strike is positioned on the female die and the guide 20 extended therethrough into the aperture 17. The male member of the die is then forced downwardly such as by a hammer blow into the position shown in Fig. 2, thus deforming the strike along the locking edge 14 by forcing the metal thereof downwardly into the concavity 18. Thus the completed strike as shown in Fig. 3 presents a concave surface 22 along the locking edge 14 on that side of the strike toward which the lip 13 is bent. On the opposite side of the strike there will be a corresponding bulge or protuberance or embossment indicated at 23. In this manner the locking edge 14 will be projected outwardly from the plane of the body of the strike in a direction opposite that from which the lip 13 is bent. As this bulge or embossment merges smoothly with the lip 13 the bolt or latch of the strike, after engaging the lip, will ride upwardly over the convex surface 23 before being projected through the aperture 12 to engage the locking edge 14.

As most conventional strikes are formed of malleable brass this deformation of the strike by means of the die can be easily accomplished with only one or two hammer blows on the male member 19, and once being deformed by the die the metal will retain its deformed shape without springing back. The strike thus produced or deformed can frequently be used to advantage as the projection of the locking edge 14 is frequently sufficient to have the bolt engage it to hold the door in closed position.

It is contemplated within the scope of the invention to distribute as a manufactured article strikes as illustrated in Fig. 3. However, in many instances the fit between the door and the door jamb is such that the protuberance or embossment at 23 is not necessary and may be undesirable. In such an event the improved strike may be positioned on a flat anvil 24 and the metal at the protuberance flattened out such as by a hammer H, as shown in Fig. 4, thus returning the strike from the position shown in Fig. 3 to the form of a conventional strike as shown in Fig. 1.

From the above described construction it will be appreciated that an improved strike has been provided which may be advantageously employed in many situations wherein the strike as mounted on a door jamb is located too remote from the door lock as mounted on the door. Also, a die for producing the same has been provided that may be conveniently carried and utilized by carpenters to modify or deform conventional strikes to produce strikes embodying the present invention.

Various changes may be made in the details of construction without departing from the spirit and scope of the invention as defined by the appended claims.

I claim:

1. A strike for door locks comprising a section of sheet metal having an aperture therethrough adapted to receive a bolt of a door lock and having a laterally bent lip along one edge engageable by the bolt in the course of the closing of the door on which the lock is mounted to force the bolt into retracted position from which it may enter the aperture, the metal of the strike adjacent the edge of the aperture which is most adjacent the lip being bent out of the plane of said section in the opposite direction from that in which the lip is bent.

2. A strike for door locks comprising a section of sheet metal having an aperture therethrough adapted to receive the bolt of a door lock and one edge of which serves as a locking edge engageable by the bolt, the metal of the strike along said edge being bent outwardly out of the plane of the strike so as to extend toward the edge of the door with whose door lock the strike is adapted to be associated.
